UNITED STATES PATENT OFFICE

GEORGE WALD, OF BELLEVILLE, ILLINOIS

RADIO TUNING DEVICE

Application filed April 30, 1930. Serial No. 448,462.

This invention relates to improvements in radio tuning devices, and consists in the novel construction hereinafter disclosed.

An object of the invention is to provide, in a tuning system for radio receiving circuits, a tuning device comprising a helical condenser including a plurality of units whereby separate stages of radio frequency, or separate stages of radio frequency and an oscillator circuit, may be simultaneously tuned for the reception of wave lengths of wide variation.

A further object of the invention is to provide a novel construction of a helical condenser unit that is compact in construction and which may be economically manufactured for quantity production.

Another object of this invention is to provide a novel radio receiving set capable of accurate tuning and with which reception is possible throughout a wave band of 10 to 600 meters.

Additional objects of the invention will be readily apparent to those skilled in the art from the following detailed description thereof, taken in connection with the accompanying drawings, in which:—

Fig. 1 is a side elevation of the condenser unit shown in association with the controlling means therefor.

Fig. 2 is a diagrammatic view of one form of radio receiving circuit with which the condenser, constituting the tuning unit, is associated.

Fig. 3 is a diagrammatic view of the transformer in an oscillator or radio frequency circuit.

Fig. 4 is a detail view of an alternate form of actuator and dial drum for the condenser unit.

Fig. 5 is a detail view illustrating a feature of construction of the stator of the condenser.

Fig. 6 is a further detail view of the same construction.

Fig. 7 is an isometric view showing the manner in which the plates of the stator of the condenser are assembled.

Figs. 8 to 13, inclusive, show the progressive forms of plates forming the helix of the condenser stator.

The condenser which comprises the tuning unit for the receiving circuit, as shown in the drawings, includes a frame having a base 1 adapted to support the unit in the case of a radio receiving set. Integrally formed

with the base 1 are standards 2, 3 and 4. The standards 2 and 3 constitute the end members of the condenser frame, and the standard 4 constitutes a journal support for the rotor of the condenser. The condenser cage supporting the stator plates comprises circular end plates 5 and 6 of electrically non-conductive material and bars or strips 7 extending longitudinally between the members 5 and 6 and secured, respectively, to the peripheries thereof. The strips 7 are spaced equally circumferentially at 60° apart. The condenser cage is secured in the condenser frame by a pair of screws 8 that extend through the standard 3 into the end member 5 and a pair of screws 9 that extend through the standard 2 and through a spacing block 10 and into the face of the member 6. The condenser frame is made of electrically conductive material and is grounded at 11. Each of the members 7 adjacent to the right end, as viewed in Fig. 1 is provided with electrically conductive inset strips 12 for a purpose hereinafter to be described.

A stud shaft 13 extends axially into the condenser cage at one end thereof, one end of said shaft being supported in the plate 6 in which it is rotatively mechanically secured and the other end extending for some distance into the condenser cage. This shaft 13 is non-rotated, however, except for the slight adjustment hereinafter described. This shaft has a spiral slot 14 cut in its face.

A revoluble shaft 15 extends into the opposite end of the condenser cage and has an extension that is journaled for rotation in the standards 3 and 4. The inner end of the shaft 15 carries a sleeve 16 which is coupled with the shaft 15 by a pin-and-slot connection 17. The sleeve 16 constitutes the hub of the rotor helices of the condenser and for the dial drum.

The sleeve 16 has a pin 18 on its inner face and near its open end, said pin 18 being adapted to ride in the spiral slot 14. Thus, as the shaft 15 is rotated in one direction, the sleeve 16 by reason of the pin-and-slot connection 17 will rotate with the shaft and will travel inwardly by reason of the pin 18 riding in the slot 14. When the shaft 15 is rotated in the opposite direction the sleeve 16 will move outwardly from the shaft 13. The rotor elements of the condenser are carried by the sleeve 16, and by the operation of the shaft 15 will be moved into

and out of condensive relationship with the stator elements to a greater or lesser degree, as will be more fully hereinafter explained.

Any suitable means may be provided for 5 rotating the shaft 15. In the embodiment shown in Fig. 1 of the drawings the actuator for the shaft 15 comprises a pulley 19 supported on a shaft 20 which shaft may be revolved by a knob (not shown) accessible from 10 the outside of the radio receiving set case. The pulley 19 is operatively connected with a pulley 21, pinned to the shaft 15, by a flexible connection 22. The faces of the pulleys 19 and 21 may be arranged at any suitable 15 angle so as to position the operating knob at a convenient place in the panel of the radio receiving set case. The shaft 15 is held in proper longitudinal adjustment by collars 23 and 24 pinned to said shaft 15 and abutting 20 respectively against the faces of the shaft journals in the standards 3 and 4.

In Fig. 4 of the drawings a modification 25 of the arrangement for operating the condenser shaft is shown, and in this figure is also shown an alternate arrangement of an 30 indicating drum. In this embodiment a pulley, corresponding to the pulley 19 and therefore similarly numbered, is operatively connected with a pulley on the shaft 15 corresponding 35 to the pulley 21 and therefore similarly numbered and with a separate pulley 25 which operates a shaft 26 on which the dial drum is carried. The connection for operating the pulleys 21 and 25 comprises 40 a flexible connection corresponding to the connection 22 and therefore similarly numbered. The differences between this construction and the construction shown in Fig. 1 is that the ratio between the pulleys 21 and 25 is such that the degree of rotation of the 45 pulley 25 is half that of the pulley 21. Therefore, the dial travels half the rate of the travel of the condenser rotor; whereas in Fig. 1 the dial is carried by the sleeve 16, and therefore makes the same number of turns as the rotor and advances with it.

The shaft upon which the pulley 19 of Fig. 4 is mounted corresponds to the shaft 20 of Fig. 1 and therefore is similarly numbered. 50 In Fig. 4 this shaft is shown as operated by a knob 27 on the outside of the panel of the radio receiving set case.

In Fig. 1 the dial is in the form of a cylinder on the periphery of which there is a 55 spiral scale, said dial being mounted upon the end of the sleeve 16 and turning therewith. In Fig. 4 a similar scale (not shown) is mounted on a drum that is carried by the shaft 26. The dial in both instances constitutes means for guiding the adjustment of 60 the rotor of the condenser.

The stator portion of the condenser that is supported in the condenser cage is constructed in a novel manner and includes generally 65 three consecutive series of plates, the

forms of which are shown specifically in Figs. 8 to 13 of the drawings, so arranged as to form three separate helices. The plates are designed to be formed from sections stamped by standard dies which when assembled 70 form a helix of increasing area. As specifically shown, each helix consists of six plates, the form of each being shown respectively in Figs. 8 to 13, inclusive. They may be punched from flat stock and then deformed 75 to constitute a part of a continuous helix. The split ends are deflected to give a pitch of approximately three-eighths of an inch to the helix thread. Each plate is provided with lugs 29, 30 and 31 by means of which 80 they are secured in slots formed in the inner face of the member 7.

The method of assembling the plates to form the three helices is as follows:

A series of three plates, as shown in Fig. 85 8, are placed side by side in the condenser cage. The three plates of Fig. 8 are then placed in the condenser cage so that the lugs 29, 30, and 31, seat in slots formed in the inner face of the members 7, the lugs 29 of 90 each of the three plates being displaced 120° from each other. The remaining plates shown in Figs. 9 to 13, inclusive, are similarly assembled, the lugs 29, 30 and 31, being placed in the same respective slots as the corresponding lugs on other plates of the same series. The plates of each helix are matched at their ends thereby forming three continuous helices arranged side by side and interthreaded, each helix increasing in area 95 from its inner end toward the outer end thereof. All of the lugs 29 of each series are in contact with the respective inset conductor bars 12 in the members 7, and the corresponding lugs 30 and 31 contact with the 100 diametrically opposite bars 12.

In assembling the plates in the condenser cage a spacing template may be used to properly position the lugs in the respective slots in which they are mounted and, after the plates are positioned, they may be soldered 110 in place, or spacing washers may be used between the plates and they may be clamped in place by a suitable construction, if desired. It will thus be seen that the three stator units are secured in the condenser cage so that the beginning of each stator unit, as well as their termination, is 120° apart. Or the beginning of all the stator and rotor units may be on the same line, but the stator plates so stamped out as to have lugs 29, 30 and 31 of each unit displaced 120° on their circumferences.

Three leads 32, 33 and 34 are taken off the 115 respective bars 12 for connecting the separate stator units of the condenser into the radio receiving circuit, as will be more fully explained hereinafter.

The rotor of the condenser is made up of 120 three helices similarly assembled from series

of similar plates, except that the plates of the rotor are uniform in area. The three rotor helices have the beginning of their threads separated by 120° corresponding to the arrangement of the stator helices. A convenient method of assembling the plates on the sleeve 16 is to provide the sleeve with a series of spiral thread grooves and to solder the rotor plates in said grooves.

12 It should be noted, therefore, that in the construction of the stator and rotor units of the condenser there is provided three series of helices for the stator which are adapted to be brought into condensive inter-relation 15 with the three helices of the rotor. The condensive surface relationship between the rotor plates and the stator plates gradually increases as the rotor is moved into the stator by the rotation of the shaft 15 in one direction, and decreased as the shaft is rotated in the opposite direction.

The distance between the rotor and stator plates is approximately one-sixteenth of an inch less the thickness of two plates. This 25 distance may be slightly regulated by a construction for adjusting the rotative position of the shaft 13. The shaft 13 extends through the end plate 6 and is provided with a knurled knob 35 by which it may be given a slight 30 rotation to change the relationship of the slot 14 to the thread of the stator helices. A set screw 36 extends through a slot 37 in the knob 35 and into the plate 6 and provides 35 means for setting the adjustment effected by the knob 35, which adjustment is limited by the length of the slot 37.

The plates shown in Figs. 12 and 13 may 40 preferably be made of a greater thickness than the remaining plates, and, therefore, the dielectric space between the rotor and stator plates is reduced. This results in an 45 effective capacity for these plates double that of the area. The result of this is that tuning can be effected by the last three turns 50 of the condenser to a wave band of from 200 to 600 meters, while the first three turns are utilized to tune in a wave band of 10 to 150 meters.

55 In place of arranging the plates of the condenser stator in interfitting relationship, they may be arranged in consecutive longitudinal positions and the plates of the rotor may also be arranged in corresponding longitudinal alignment to cooperate with the separated stator units, in which event the pitch of the helices of both the rotor and the stator may be decreased. The modified form of actuator illustrated in Fig. 4 may be utilized with this construction so that the dial may have the scale with suitable intervals to indicate the position of the condenser elements.

60 In Fig. 2 of the drawings there is illustrated a radio receiving circuit into which the condenser of the construction hereinbe-

fore described is connected. It will be unnecessary to describe the various circuits as the undescribed portion of the diagram will be readily recognized as the standard construction of a heterodyne circuit. The manner in which the condensers are connected into the receiving circuit, together with the control of the secondary of an oscillator circuit and of one of the radio frequency circuits before the detector, provides for tuning the receiving set to a wide variation of radio frequency. This is accomplished by controlling the induction of the secondary of the oscillator and the radio frequency circuits and by controlling the capacity of the condenser in co-ordination with the induction. A represents the oscillator circuit and B and C represent the radio frequency circuits with which we are primarily concerned.

70 In Fig. 3 of the drawings is shown a diagram of the particular form of transformer employed both in the oscillator and radio frequency circuits A and B.

75 By reference to the circuit B it will be noted that the circuit consists of an untuned vacuum tube 38, the plate of which connects through a primary 39 to B + 160 v. The primary has, for example, twenty to twenty-five turns and is wound on a spool or holder 40 (Fig. 3), which spool or holder also carries a part of the secondary winding. The primary and the portion of the secondary that is wound on the spool 40 has a one to one ratio and has an induction of approximately 103 m. henries. Adjacent to the spool 40 and in the same magnetic path is a second spool 41 upon which is wound the remainder of the secondary, for example, 70 to 80 turns, and has an induction of approximately 205 m. henries.

80 The windings of the secondary on the spool 40 is indicated by 42 (Fig. 2) and that portion of the secondary wound on the spool 41 is indicated by 43 (Fig. 2). It will be understood that the magnetic path between the two portions of the secondary is continuous. Therefore, the total induction when both portions of the secondary are connected is the sum of their separate induction or approximately 308 m. henries. The portion of the secondary 43 is cut in and out by the switch 44. The transformer therefore may be controlled to provide an induction either of 103 m. henries or 308 m. henries, for example.

85 By reference to Fig. 2 it will be noted that the switch 44 is so connected with the second radio frequency circuit C that when the switch is down the second stage of radio frequency is cut out.

90 When the leads 32, 33 and 34 from the respective helices of the condenser are connected to the circuits B, C and A, respectively, as shown in Fig. 1, the capacity and in-

ductance of the circuits are balanced to produce resonance at predetermined frequencies in any rotation of the condenser, i. e. the inductance in each of the circuits being the same and an equal amount of capacity being added at all times to produce resonance for the selected frequency. By operating the switch 44 the induction in the circuits A and B are reduced because of cutting out the supplemental turns of the secondaries of their transformers and the circuit C is cut out.

The following table gives the capacity in m. farads required for the necessary resonance of a circuit when employed with the transformer specifically illustrated and described adapted to produce an inductance "L" of either 308 or 103 m. henries, in order to tune to the various wave lengths or frequencies as indicated in the table:

	Wave length in meters	Frequencies in k.c.	Approximate capacity required when "L" 308 m. henries	Approximate capacity required when "L" 103 m. henries
25	600	500	.000375 m.f.	
	500	600	.000268 m.f.	
	400	750	.000162 m.f.	
	300	1,000	.000095 m.f.	
	200	1,500	.000045 m.f.	
	150	2,000	.000024 m.f.	.000007 m.f.
30	100	3,000		.000027 m.f.
	75	4,000		.000017 m.f.
	60	5,000		.000011 m.f.
	50	6,000		.000008 m.f.
	40	7,500		.000005 m.f.
	30	10,000		.000003 m.f.
	20	15,000		.0000014 m.f.
35	15	20,000		.00000048 m.f.
	10	30,000		.00000027 m.f.

In the following table is shown the areas of the plates illustrated respectively in Figs. 8 to 13 of the drawings, assuming an exterior diameter of 4.5 inches and approximate interior diameters as shown in the second column. In the last column is shown the capacity of the condenser when a rotor helix has been advanced in steps respectively so that it adjoins the several plates. The capacities for plates Nos. 12 and 13 are based upon corrected computations due to a narrower air gap adjacent those plates, as described above:

	Plate No.	Approximate average interior diameter— inches	Approximate area (one side) sq. inches	Capacity m.f.
50				
55	8	4"	3.1416	.00001125
	9	3 $\frac{3}{8}$ "	6.9586	.0000375
	10	2 $\frac{3}{4}$ "	9.9667	.000075
	11	2 $\frac{3}{8}$ "	12.3543	.0012
	12	1 $\frac{1}{2}$ "	18.	.002565
60	13	1"	19.25	.009375

By a comparison of the above tables, it will be seen that the construction of the condenser is such as to provide a graduated capacity

sufficient with the two inductance values to permit the tuning of a circuit for the full wave band for 10 to 600 meters.

From the foregoing description it will be apparent that the invention accomplishes its object.

While a particular radio receiving circuit is shown, the application of the invention is not limited to that particular circuit, but as may be apparent, the invention is applicable to a wide range of receiving circuits employing balanced circuits. It is to be understood that otherwise the invention is not limited to the details as shown and described, but that parts of the invention may be used to advantage without the whole, and that various changes may be made in the details of construction within the scope of the appended claims without departing from the scope of this invention.

I claim:

1. A condenser having a pair of helical plates, and means for progressively advancing one plate into position with the other, one of said plates comprising a plurality of circular sections distorted to form an integral part of a helix, each of said sections having an end coincident with an end of an adjacent section, and one of said sections being thicker than others to reduce the air gap between it and the cooperating plate.

2. A condenser comprising a plurality of helical stator plates in intertwined relationship, a plurality of helical rotor plates in intertwined relationship carried by a common supporting element, each of said rotor plates being adapted to cooperate with a stator plate, and means for simultaneously rotating and longitudinally moving said supporting member whereby each of said rotor plates will be simultaneously moved into cooperation with a stator plate.

3. A condenser comprising a plurality of helical stator plates in intertwined relationship, a plurality of helical rotor plates in intertwined relationship carried by a common supporting element, each of said rotor plates being adapted to cooperate with a stator plate, means for simultaneously rotating and longitudinally moving said supporting member whereby each of said rotor plates will be simultaneously moved into cooperation with a stator plate, and an indicating drum mounted on said supporting member.

4. A condenser comprising a plurality of like helical stator plates in intertwined relationship, a plurality of helical rotor plates corresponding in pitch and relationship to said stator plates, a common mounting for said rotor plates, and means to cause rotation and longitudinal movement of said mounting.

GEORGE WALD.
